UNITED STATES PATENT OFFICE.

CHARLES A. GREEN AND HENRY F. SCHUH, OF CHICAGO, ILLINOIS, ASSIGNEES TO
THE C. F. PEASE COMPANY, OF CHICAGO, ILLINOIS, A CORPORATION OF ILLINOIS.

DRAWING INSTRUMENT.

1,417,375.

Specification of Letters Patent. Patented May 23, 1922.

Application filed May 23, 1921. Serial No. 471,673.

To all whom it may concern:

Be it known that we, CHARLES A. GREEN and HENRY F. SCHUH, citizens of the United States, residing at Chicago, in the county of Cook and State of Illinois, have invented certain new and useful Improvements in Drawing Instruments, of which the following is a specification.

This invention relates to drawing instruments, and more particularly to means for mounting the yoke and handle of a pair of dividers or compass.

In drawing instruments consisting of a pair of pivoted legs, the legs are connected by means of a yoke and a handle is mounted on the yoke. The yoke is freely mounted on the pivot pin connecting the legs, and in prior constructions, no means have been provided for maintaining the handle in a vertical position.

In the present invention, we provide a guide member fixedly mounted with respect to the yoke and provided with a depending portion. Suitable guide members or connections are secured to each of the legs and engage the depending portion of the guide member. By means of the construction provided, the yoke and handle are retained on a line bisecting the angle formed by the pivoted legs and the handle is thus in a vertical position when the instrument is to be used.

In the accompanying drawings, we have shown one embodiment of the invention. In this showing:

Figure 1 is a side elevation of a pair of dividers showing the invention applied,

Figure 2 is an end elevation,

Figure 3 is a vertical sectional view on line 3—3 of Figure 1,

Figure 4 is a horizontal sectional view on line 4—4 of Figure 1, and,

Figure 5 is a detail view of the guide member.

Referring to the drawings, the reference numerals 1 and 2 designate the legs of the instrument. As shown, the leg 1 is provided with a needle point 3, retained in position by means of set screw 4. The leg 2 is likewise provided with a needle point 5 and fastening means 6. As shown, the leg 2 may be split longitudinally, as at 7, and a set screw 8 may be arranged in one side to permit fine adjustments.

The legs are pivotally connected to each other by means of a pivot pin 9. One end of the pin is provided with a head 10, the other end being threaded for the reception of a nut 11. The pivot pin passes through arms 12 of a yoke, the arms being arranged on opposite sides of the legs in the usual manner. The yoke is further provided with a handle or finger grip 13.

A guide member 14 is fixedly secured to the yoke. As shown, the upper end of the guide member is enlarged, as at 15, to fit over one of the arms 12, being provided with an opening 16 for the passage of the pivot pin. The sides of the guide member are provided with flanges 17, adapted to be arranged on opposite sides of the arm 12 (see Figure 4). Beneath the lower end of the arm 12, the guide member is reduced in size, as at 18, and provided with a pair of flanges 19 for the reception of a guide pin 20. This pin passes through the ends of a pair of links 21, pivotally secured to the legs, as at 22.

In the use of the instrument, the guide is maintained in alinement with the yoke by means of flanges 17. The guide pin 20 rides in the lower portion of the guideway, and when one of the legs is moved, the movement of the guide pin and links 21 causes the other leg to be moved a corresponding distance toward or away from the center of the instrument. The yoke and finger piece are thus always maintained in a plane bisecting the plane formed by the two legs of the instrument and will be in vertical position when the instrument is placed on the paper for use.

The set screw 8, extending through the two portions of the split leg, permits the outer section to be moved outwardly away from the inner section, thus permitting an adjustment independent of the adjustment of the pivoted legs.

While the invention is illustrated in connection with a pair of dividers, it may be applied to any type of instrument embodying a pair of pivoted legs and a yoke.

It is to be understood that the form of our invention herewith shown and described is to be taken as a preferred example of the same, and that various changes in the shape, size, and arrangement of parts may be resorted to without departing from the spirit

of the invention or the scope of the subjoined claims.

Having thus described our invention, we claim:

- 5 1. A drawing instrument comprising a pair of legs, a yoke pivotally connecting said legs, a guide secured thereto, said guide comprising a base and side flanges, a portion of the side flanges engaging the yoke 10 to maintain the guide in alinement with the yoke, and connections between said guide and said legs.
- 15 2. A drawing instrument comprising a pair of legs, a yoke pivotally connected to said legs, a guide secured thereto, said guide comprising a base and side flanges, a portion of the side flanges engaging the side of the yoke to maintain the yoke in alinement with the guide, said guide being provided with a depending portion arranged 20 between the legs of the instrument, a guide pin mounted in said depending portion, and

connections between said guide pin and said legs.

- 25 3. A drawing instrument comprising a pair of legs, a yoke pivoted thereto, a guide secured to said yoke, said guide comprising a base and side flanges, the upper end of said guide being substantially equal in size to the yoke to position the flanges on the side 30 of the yoke, the lower portion of the guide being reduced in size to form a guideway between the flanges, a guide pin mounted in said guideway, links pivotally connected to said guide pin, and means for pivotally connecting said links to the legs of the instrument.

In testimony whereof we affix our signatures in presence of two witnesses.

CHARLES A. GREEN.
HENRY F. SCHUH.
